Control Corporation, Cambridge, Mass., a cor-
poration of Massachusetts

Application June 22, 1951, Serial No. 233,054

4 Claims. (Cl. 200—122)

1

This invention relates to a new and improved thermally actuated time delay switch which is especially suited for application as a safety switch in burner installations.

A principal object of this invention is to provide a mechanically and electrically reliable time delay switch of simple structure which can be easily and inexpensively fabricated.

It is contemplated that the switch structure of this invention may be utilized to advantage in conventional combustion control circuits wherein it is desired to operate safety apparatus, or initiate other operations, a timed interval after the failure of the burners of a furnace to operate in the proper manner. It should be understood, however, that the switch structure of this invention may be utilized to advantage in other applications wherein a delayed switching operation is desired.

The structure of a preferred embodiment of the novel switch herein described comprises a bimetal contact actuating element thermally coupled to a heater winding. A contact supporting arm is pivotally mounted to one end of said contact actuating element so that a force applied by a spring connected between said contact actuating element and said contact supporting arm will cause the contact supporting arm to move to the left or to the right, depending upon the positioning of the bimetal contact actuating element. In particular, if current flows through the heater winding for a sufficiently long period of time, the bimetal contact actuating element will curve in a conventional manner causing the contact supporting arm to move the contacts thereon from a closed to a reset position. After the switch has operated in response to current flow through the heater winding, a manual operation of a reset plunger forces the contact supporting arm back to the closed position.

In order that all of the features of this invention and the mode of operation thereof may be readily understood, a detailed description is set forth hereinafter, with particular reference being made to the drawings, wherein:

Fig. 1 is a side elevational view of a preferred embodiment of the thermal switch of this invention, with a portion of the plunger casing in section, showing the transfer contact positioned in the closed position;

Fig. 2 is a side elevational view of the switch of Fig. 1, showing the transfer contact positioned in the reset position;

Fig. 3 is a side elevational view of the switch shown in Figs. 1 and 2, with a portion of the

2

closed contact leaf and its supporting leaf removed;

Fig. 4 is a perspective view of the switch shown in Figs. 1-3, with the contact supporting arm midway between the closed and reset positions;

Fig. 5 is an enlarged perspective view of the contact actuating mechanism shown in the previous figures.

Referring now to the drawings, and particularly to Figs. 1 and 2, the switch structure shown therein comprises two hemispherical ball contacts 5 rigidly fixed to ball contact supporting arm 6. The combination of ball contacts 5 and supporting arm 6 are pivotally mounted upon the upper bent portion of retaining piece 7 so that a single pole transfer function is provided by the two operative positions of contact 5 illustrated in Figs. 1 and 2. In particular, ball contact supporting arm 6 comprises a pair of mating teeth 8 projecting through a pair of slots located in the upper bent portion of retaining piece 7. Two pivot knees 9 are located adjacent the mating teeth whereby ball contacts 5 and their supporting arm 6 pivot about a sharp bottom edge of said knees so that contacts 5 can traverse easily from one operative position to the other.

The upper hooked portion of spring 10 is passed through a small hole in ball contact supporting arm 6, and the lower hooked portion of spring 10 is passed through a hole in the bottom hooked portion of metallic retaining piece 7 whereby a force is applied to ball contact supporting arm 6 which will cause said arm to move contacts 5 either to the left or to the right of the pivot edges of knees 9, as shown in Figs. 1 and 2, respectively.

Retaining piece 7 is mechanically coupled to bimetal actuating element 11 by a pair of rivets 12. Bimetal actuating element 11 may be constructed of any conventional bimetal alloys so that the element curves to the left in response to an increase in ambient temperature. This curvature motion of actuating element 11 is not seriously impeded by metallic retaining piece 7 inasmuch as rivets 12 have the same vertical positioning near the upper edge of actuating element 11 and also because no other rivets interconnect the two parts. For purposes of switch operation, heater winding 13 is thermally coupled to the body portion of actuating element 11 whereby said bimetal actuating element is caused to curve in the conventional manner in response to current flow through said heater winding.

Conductor 14, which is soldered to ball con-

tact supporting arm 6 and retaining piece 7, interconnects said components so that a low resistance electrical path is formed between ball contacts 5 and actuating element 11. A reliable and low resistance electrical connection may therefore be made to ball contacts 5 by connecting a conductor to lug portion 15 of actuating element 11.

When ball contact supporting arm 6 is in the position shown in Fig. 1, left ball contact 5 rests against contact 16, which contact is mechanically coupled to bimetal contact leaf 17. When ball contact supporting arm 6 is in the position shown in Fig. 2, right ball contact 5 rests against reset contact 18, which contact is mechanically coupled to metallic reset contact leaf 19.

Contact leaf 17 is constructed of bimetal having the same temperature coefficient of curvature as actuating element 11. With such an arrangement, any variation in ambient temperature not due to current flow through heater winding 13 will be compensated for inasmuch as contact leaf 17 will follow the curvature of actuating element 11. In the usual embodiment, the metallic thickness of leaf contact 17 is inadequate to provide sufficient mechanical support for contact 16. As a consequence, contact support leaf 20, with pivot point 21 punched in the upper portion thereof, is provided to mechanically support contact leaf 17. It has been found that if contact support 20 is mechanically coupled to contact leaf 17 by pivot point 21 as shown, the temperature coefficient of curvature of contact leaf 17 is not changed so as to destroy the temperature compensation of the switch. Contact support 20 is also constructed of the same bimetal alloy used for the construction of contact leaf 17 and actuating element 11. Inasmuch as temperature compensation is not required when right ball contact 5 is in the reset position shown in Fig. 2, reset contact leaf 19 may be constructed of any material which will provide adequate mechanical support for reset contact 18. Insulation tubing 34 prevents the possible shorting of the terminal conductors of heater winding 13 by metallic contact leaf 19.

The switch structure shown in the drawing provides for a transfer switch operation because ball contacts 5 may be positioned either against contact 16 or reset contact 18. Suitable electrical connections may be made to the switching portions of this structure by contact with the bottom lug portions 22, 15 and 23 of contact leaf 17, actuating element 11 and reset contact leaf 19, respectively. Contact leaf 17, together with support leaf 20, actuating element 11, and reset contact leaf 19 are mechanically spaced and electrically insulated from one another by insulating spacers 24, which spacers are firmly fixed to one another by spacer bolt 25. A large hole (not shown) is provided in the portions of contact leaf 17, support leaf 20, actuating element 11, and reset contact leaf 19 between insulating spacers 24 so that spacer bolt 25 will not electrically short these components to one another. The shaft portion of bolt 25 is also preferably enclosed within an insulating tubing (not shown) to definitely assure against possible shorting.

Reset plunger 26 is mechanically supported by support piece 27, and the combination thereof is fixed to the insulating spacers 24 combination by means of spacer bolt 25. Reset plunger 26 is partially positioned within plunger casing 28, which casing is mechanically coupled to support piece 27. Compression spring 29, positioned with-

in casing 28 and shown in Fig. 1, applies a force to plunger 26 so that plunger push button 30 normally projects from the plunger casing 28 as shown in the drawings. Retaining ring 31 defines the maximum limit of the plunger push button projection.

The detailed description of the operation of the structure of this invention is as follows. Initially, contact supporting arm 6 and contacts 5 are in the position shown in Fig. 1, having been so positioned by a manual operation of plunger 26 in a manner hereinafter described in detail. Left ball contact 5 is firmly positioned against contact 16 by a downwardly directed force applied by spring 10 to contact supporting arm 6. In particular, inasmuch as this force is directed in a line which passes to the left of the pivot edges of knees 9, contacts 5 are rotated in a counterclockwise direction until they assume the position shown in Fig. 1. The physical displacement of contact leaf 17 is minimized by a force applied by contact support leaf 20 through pivot point 21.

If a potential source is applied to the terminal connections of heater winding 13 at this time, current flow therethrough will heat contact actuating element 11 in a conventional manner and cause a bending curvature of said element to the left. When this curvature is sufficiently great, the force applied by spring 10 to contact support arm 6 will be directed in a line which now passes to the right of the pivot edges of knees 9. With such an occurrence, contact support arm 6 and contacts 5 are rotated clockwise by the snap action of the force of spring 10 until right ball contact 5 rests against reset contact 18. Contacts 5 and contact support arm 6 will maintain the reset position illustrated in Fig. 2, notwithstanding the subsequent termination of current flow through heater winding 13. This is because the eventual straightening of actuating element 11 in response to the absence of heat will not produce a sufficient displacement to cause the line of direction of the force applied by spring 10 to pass to the left of the pivot edges of knees 9.

It is contemplated, for combustion control safety operation, that the electrical connections be made to lugs 15 and 23 so that a safety device, such as an audible alarm or flame failure safeguard apparatus, will be actuated in response to the reset positioning of the switch due to prolonged heating by heater winding 13. Thereafter, to reset the switch to its initial or operating position shown in Fig. 1, it is necessary to manually force plunger push button 30 within casing 28 so that spring 29 will be compressed whereby reset surface 32 of plunger 26 will mechanically bend reset contact leaf 19, and end surface 33 of plunger 26 will mechanically bend contact leaf 17 sufficiently to cause ball contacts 5 and supporting arm 6 to snap back to the position shown in Fig. 1. With the switch in said position, the manual force applied to plunger push button 30 may be released and the operative functions provided by the resting of left contact 5 against contact 16 will again be initiated. If a potential is again applied to heater winding 13, the cycle of operations hereinbefore described will occur until the switch again assumes the positioning shown in Fig. 2. Thereafter, another reset operation will be required to reposition the switch.

It may be readily appreciated that under certain conditions of high ambient temperature, sufficient curvature of contact actuating element 11 may occur without current flow in heater

winding 13 to actuate the switch from the position shown in Fig. 1 to the position shown in Fig. 2. To prevent such an occurrence, it is preferable that contact leaf 17 be constructed of the same bimetal alloy that was utilized in the construction of actuating element 11. With this arrangement, generally speaking, any increase in ambient temperature will cause a conventional displacement of both contact leaf 17 and contact actuating element 11 so that the force applied by spring 19 will continue to be directed to the left of the pivot edges of knees 9. Consequently, the thermal switch of this invention is temperature compensated and may be actuated only by sustained current flow through heater winding 13.

It is to be understood that the above described arrangements are illustrative of the application of the principles of this invention. Numerous other arrangements may be devised by those skilled in the art without departing from the scope of this invention.

What is claimed is:

1. A thermally actuated time delay switch comprising a bimetallic contact actuating element having a heater winding thermally coupled thereto, a metallic retaining piece mechanically coupled to said contact actuating element, a contact supporting arm pivotally mounted upon the upper portion of said retaining piece, said contact supporting arm having a plurality of electrical contacts positioned thereon, a spring tensioned between said contact supporting arm and the lower portion of said retaining piece whereby the bending of said contact actuating element in response to thermal energy from said heater winding causes the line of direction of said spring force to reverse sides with respect to the pivot points of said contact supporting arm, and a plurality of contact leaves supporting stationary contacts disposed in a contact mating relationship with the contacts of said contact actuating element.

2. A thermally actuated time delay switch comprising a bimetallic contact actuating element having a heater winding thermally coupled thereto, a metallic retaining piece mechanically coupled to said contact actuating element, a contact supporting arm pivotally mounted upon the upper portion of said retaining piece, said contact supporting arm having a plurality of electrical contacts positioned thereon, a spring tensioned between said contact supporting arm and the lower portion of said retaining piece whereby the bending of said contact actuating element in response to thermal energy from said heater winding causes the line of direction of said spring force to reverse sides with respect to the pivot points of said contact supporting arm, a plurality of contact leaves supporting stationary contacts disposed in a contact mating relationship with respect to the contacts of said contact actuating element, one of said contact leaves being constructed of the same bimetal used in the construction of said contact actuating element, and a reset plunger for applying a bending force to said plurality of contact leaves whereby one of the contacts of said contact supporting arm may be manually positioned against the mating contact of said bimetal contact leaf.

3. A thermally actuated time delay switch comprising a bimetallic contact actuating element having a heater winding thermally coupled there-

to, a metallic retaining piece mechanically coupled to said contact actuating element, a contact supporting arm pivotally mounted upon the upper portion of said retaining piece, said contact supporting arm having a plurality of electrical contacts positioned thereon, a spring tensioned between said contact supporting arm and the lower portion of said retaining piece whereby the bending of said contact actuating element in response to thermal energy from said heater winding causes the line of direction of said spring force to reverse sides with respect to the pivot points of said contact supporting arm, a plurality of contact leaves supporting stationary contacts disposed in a contact mating relationship with the contacts of said contact actuating element, one of said contact leaves being constructed of the same bimetal used in the construction of said contact actuating element, a bimetal supporting leaf applying a supporting force to said bimetal contact leaf through pivot means, and a reset plunger for applying a bending force to said plurality of contact leaves whereby one of the contacts of said contact supporting arm may be manually positioned against the mating contact of said bimetal contact leaf.

4. A thermally actuated time delay switch comprising a bimetallic contact actuating element having a heater winding thermally coupled thereto, a metallic retaining piece mechanically coupled to said contact actuating element and having an upper bent portion projecting at a substantially normal angle with respect to said contact actuating element and a lower hooked portion projecting through a hole in said contact actuating element, a contact supporting arm including a pair of pivot knees pivotally mounted upon the upper bent portion of said retaining piece, said contact supporting arm having a plurality of ball-type electrical contacts positioned thereon, a spring tensioned between said contact supporting arm and the lower hooked portion of said retaining piece whereby the bending of said contact actuating element in response to thermal energy from said heater winding causes the line of direction of said spring force to reverse sides with respect to the pivot points of said pivot knees, a plurality of contact leaves disposed in a parallel relationship with respect to said contact actuating element, each of said contact leaves having an electrical contact positioned thereon so as to mate with a different one of the contacts of said contact supporting arm, one of said contact leaves being constructed of the same bimetal used in the construction of said contact actuating element, a bimetal supporting leaf applying a supporting force to said bimetal contact leaf through pivot means, and a reset plunger for applying a bending force to said plurality of contact leaves whereby one of the contacts of said contact supporting arm may be manually positioned against the mating contact of said bimetal contact leaf.
